DISPENSER HEAD

Carl S. Zilk, 6312 SE. 48th Ave., Portland, Oreg.

Filed May 17, 1962, Ser. No. 70,184

Term of patent 14 years

(Cl. D2—3)

FIG. 2

FIG. 3

FIG. 1

FIG. 4

FIG. 5

FIG. 1 is a side elevational view of a dispenser head showing my new design;

FIG. 2 is a top plan view thereof;

FIG. 3 is a front elevational view thereof;

FIG. 4 is a rear elevational view thereof; and

FIG. 5 is a bottom view thereof.

I claim:

The ornamental design for a dispenser head, as shown.
